(57) **CLAIM**

The ornamental design for a water detection assembly having a water detection housing, substantially as shown and described.

DESCRIPTION

FIG. 1 is a front perspective view of a water detection assembly having a water detection housing;

FIG. 2 is a back perspective view of the water detection assembly having a water detection housing;

FIG. 3 is a front elevational view of the water detection assembly having a water detection housing;

FIG. 4 is a back elevational view of the water detection assembly having a water detection housing;

FIG. 5 is a right side elevational view of the water detection assembly having a water detection housing;

FIG. 6 is a left side elevational view of the water detection assembly having a water detection housing;

FIG. 7 is a top plan view of the water detection assembly having a water detection housing; and,

FIG. 8 is a bottom plan view of the water detection assembly having a water detection housing.

Phantom lines, where utilized, are for illustrative purposes only and form no part of the claimed design.
